(57) **CLAIM**

The ornamental design for a butterfly shaped container, as shown and described.

DESCRIPTION

FIG. 1 is a back perspective view showing the new design of a butterfly shaped container;

FIG. 2 is a bottom perspective view thereof;

FIG. 3 is a rear view thereof;

FIG. 4 is a front view thereof;

FIG. 5 is a top view thereof;

FIG. 6 is a bottom view thereof;

FIG. 7 is a left side view thereof;

FIG. 8 is a right side view thereof;

FIG. 9 is a perspective view of the butterfly shaped container shown in an alternate configuration in an open position;

FIG. 10 is a rear view thereof;

FIG. 11 is a front view thereof;

FIG. 12 is a left side view thereof;

FIG. 13 is a right side view thereof;

FIG. 14 is a top view thereof;

FIG. 15 is a bottom view thereof; and,

FIG. 16 is a perspective view of the butterfly shaped container shown in an alternative configuration in an open position with bowls.

The dashed lines of FIGS. 2, 7 and 15 show portions of the butterfly shaped container that form no part of the claimed design. The dash lines of FIG. 16 depicting bowls show environmental conditions only and form no part of the claimed design.
